UNITED STATES PATENT OFFICE.

SALVATORE PICCIOTTO, OF NEW YORK, N. Y.

WEIGHT-MOTOR DEVICE.

1,426,598.

Specification of Letters Patent. Patented Aug. 22, 1922.

Application filed April 29, 1921. Serial No. 465,496.

To all whom it may concern:

Be it known that I, SALVATORE PICCIOTTO, a subject of the King of Italy, residing at New York, in the county and State of New York, have invented new and useful Improvements in Weight-Motor Devices, of which the following is a specification.

The objects of my invention are first, to provide a weight motor device which shall 10 be simple in construction and efficient in operation.

Second, to provide a device which, by reason of its peculiar construction sets into motion a pendulum, the oscillations of which 15 operate a dynamo.

Third, to provide a weight motor device which can be easily rewound without disturbing its operation.

With these objects in view, others appearing as the specification proceeds, and the 20 nature of the invention more fully appears, the invention comprises essentially, a gear mechanism operated by a weight, a pendulum operatively connected to the gear mechanism, and a flywheel, actuated by oscillation of said pendulum, to drive the dynamo.

The invention relies on certain refinements of construction to make the device ultimately effective as a weight motor.

In the accompanying drawings I have 30 shown an example capable of applying the principles stated, and in the drawing like reference-characters, indicate corresponding parts throughout the several views. The 35 several figures of the drawings are briefly described as follows:

Figure 1, is a front elevation of my device,

Figure 2, is a plan view of the pendulum 40 with connecting levers attached to shaft comprising part of gear mechanism,

Figure 3, is an end elevation of the upper section of the device showing the gear mechanism, and

Figure 4, is an end elevation of the lower section of the device showing the flywheel and means to rotate same.

Referring to details in drawings:

Chain 1 engages with teeth of sprocket 2, 50 passes over pulleys 3, 4, 5, 6, 7, engages with teeth of sprocket 8, passes over pulleys 9, 10, then by means of pulley 11, carries weight 12, and is then joined forming a continuous chain. Between pulleys 3, 4, by 55 means of pulley 13 a counterweight 14 is

suspended on said chain 1 to prevent slackening. (Fig. 1.)

Sprockets 15 and 2, are carried on shaft 16, and chain 17 engages with teeth of sprocket 15 and drives sprocket 18 carried 60 on shaft 19 with gear 20. Said gear 20 engages with teeth of pinion 21, which with gear 22, is carried on shaft 23.

Shaft 24 carries arm 25 and pinion 26 which meshes with teeth of gear 22, and is 65 consequently driven by same. (Figures 1-3.)

It can be readily seen that, by this arrangement, the revolutions of shaft 24, are greatly increased in number over those of 70 shaft 16.

Pendulum 27 swings on axis 28, 29 rigidly fastened to frames 30, 31, and consists of uprights having pivoted crossbars. Said crossbars strengthening said pendulum 27, 75 allows it to oscillate in a straight line. Connecting rod 32 is pivotally attached to arm 25 and to pendulum 27, transferring to same the motion derived from pinon 26. (Figures 1-2.)

To rotate the flywheel 33 a three-piece connecting rod is employed. The upper end of connecting rod 34 is centrally pivoted to pendulum 27, and the lower end is pivoted to arm 35, which is fastened to axis 36 of flywheel 33. The center piece of rod 34 pivotally unites the same and is guided by casing 37, in order to transfer a uniform rotating motion to flywheel 33, which by means of belt 38, drives dynamo 39. (Figures 1-4.) 80 90

The result of this arrangement of the instrumentalities before described is to produce an increase in the revolutions imparted to the driven member so as to be double the rate of rotation of the driving pinion 26. 95 That is to say, that as the pendulum device 27 swings toward the right from its vertical position under the actuation of the driving member 26 during a quarter of a revolution of the arm 25, the crank arm 35 of the 100 driven member is raised from its lowermost position to the uppermost position giving one-half revolution to the flywheel.

The return movement to the vertical position moves the arm 35 to its lowermost position or another half revolution, and the corresponding swinging movement of the pendulum in the opposite direction to the vertical produces the second complete revolution so that the fly-wheel has translated to it two 110

revolutions to each single revolution of the driving pinion 26.

The axis 40 of sprocket 8 carries ratchet 41, which engages with pawl 42 pivoted on frame 30. To actuate this device crank 43 fastened to the outer end of axis 40, is turned from left to right, causing ratchet 41 to be free from pawl 42. The teeth of sprocket 8 which are engaged with chain 1, 10 will drive same downward.

This causes weight 12 to be raised up while counterweight 14 is taking up the slack of chain 1, consequently lowers. Pawl 42 will not permit chain 1 to move upward 15 in order to allow weight 12 to descend, consequently chain 1, which is also engaged with teeth of sprocket 2 will force same to rotate and chain 17 will then drive sprocket 18 and gear 20.

20 Said gear 20 being in mesh with pinion 21, will drive same and also gear 22, which engaging with teeth of pinion 26 will rotate same and consequently arm 25. Said arm 25

revolving causes pendulum 27 to oscillate, which in doing so will turn the flywheel 33. 25

Having thus described my invention, what I claim as new and desire to secure by Letters Patent is:

A weight motor of the class described, comprising a frame support, a driving gear 30 mounted therein, weight means operatively connected to said driving gear to actuate the same, a pendulum swingingly carried by said frame and operatively connected to the driving gear, a driven member, and a pitman connection intermediate the pendulum and the driven member whereby a single rotation of the driving gear will impart double rotation to the driven member.

In testimony whereof I have set my hand 40 in the presence of two subscribing witnesses.

SALVATORE PICCIOTTO.

Witnesses:

SALVATOR ODDO,
LEONE ROVERIN.
